DESIGN FOR AN ELECTRIC LAMP OR SIMILAR ARTICLE

Abraham L. Buschman, New York, N. Y.

Application April 15, 1937, Serial No. 68,791

Term of patent 14 years

To all whom it may concern:

Be it known that Abraham L. Buschman, a citizen of the United States and resident of New York, in the county of New York and State of New York, has invented a new, original, and ornamental Design for an Electric Lamp or Similar Article, of which the following is a specification, reference being had to the accompanying drawing, forming part thereof, in which,

Fig. 1 is a side elevational view of an electric lamp embodying my design;

Fig. 2 is a top plan view thereof;
Fig. 3 is a bottom plan view thereof; and
Fig. 4 is a longitudinal cross-sectional view thereof.

The design is characterized by the inner configuration viewed from the outside of the lamp, as in Fig. 1 of the drawing.

I claim:

The ornamental design for an electric lamp or similar article, as shown and described.

ABRAHAM L. BUSCHMAN.
